UNITED STATES PATENT OFFICE

155,815

DESIGN FOR A PORTABLE LOADER

Herbert F. Lessmann, Des Moines, Iowa

Application October 6, 1947, Serial No. 141,761

Term of patent 14 years

(Cl. D14—3)

To all whom it may concern:

Be it known that I, Herbert F. Lessmann, a citizen of the United States, and resident of Des Moines, Iowa, in the county of Polk and State of Iowa, have invented a new, original, and ornamental Design for a Portable Loader, of which the following is a specification, reference being had to the accompanying drawing, forming part thereof, in which:

Fig. 1 is a side elevational view of a portable loader, showing my new design with the scoop in a lowered position therefor;

Fig. 2 is a side elevational view of the portable loader with the scoop in a raised position therefor;

Fig. 3 is a front view looking toward the right in Fig. 2;

Fig. 4 is a rear view of the loader with the scoop in a partially raised position; and

Fig. 5 is a front perspective view of the portable loader with the scoop in a raised position.

I claim:

The ornamental design for a portable loader, substantially as shown.

HERBERT F. LESSMANN.
